(57) **CLAIM**

I claim the ornamental design for a belt wedge, as shown and described.

DESCRIPTION

FIG. 1 is a perspective view of a belt wedge showing my new design;

FIG. 2 is a rear perspective view thereof, with the broken lines depicting a belt shown broken away for convenience of illustration;

FIG. 3 is a rear elevational view thereof;

FIG. 4 is a front elevational view thereof;

FIG. 5 is a right side view thereof with the broken lines depicting a belt removed;

FIG. 6 is a left side view thereof with the broken lines depicting a belt removed;

FIG. 7 is a top view thereof, with the broken lines depicting a belt shown broken away for convenience of illustration;

FIG. 8 is a bottom view thereof;

FIG. 9 is a top view thereof shown in a position of use; and,

FIG. 10 is a rear perspective view thereof shown in a position of use.

In the drawings, the dot-dash broken lines depict the boundaries of the claim and form no part thereof. All remaining broken lines depict environmental structure that forms no part of the claim.
